UNITED STATES PATENT OFFICE.

JOHN R. WHITTEMORE, OF ERIE, PENNSYLVANIA.

CRANE MECHANISM.

No. 809,481.

Specification of Letters Patent.

Patented Jan. 9, 1906.

Application filed May 13, 1905. Serial No. 260,320.

To all whom it may concern:

Be it known that I, JOHN R. WHITTEMORE, a citizen of the United States, residing at Erie, in the county of Erie and State of Pennsylvania, have invented certain new and useful Improvements in Crane Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to improvements in crane mechanism, and has for its object a combination and arrangement of jib-cranes with a traveling crane in such a manner that a trolley-hoist mechanism will operate on both the jib and traveling cranes and pass from one to the other, so that work can be transferred from one of the jib-cranes to the traveling crane and from the traveling crane to any one of the jib-cranes, as may be desired.

A further feature of my invention is the providing of mechanism whereby the traveling crane can be locked on its track opposite any one of the jib-cranes and the jib-crane can be locked in line with the traveling crane, so that the trolley-hoist mechanism will travel from one crane to the other.

The features of this invention are herein, after set forth and described, and illustrated in the accompanying drawings, in which—

Figure 1 is a top or plan view of a combined traveling-crane and jib-crane mechanism embodying my invention. Fig. 2 is a transverse view in elevation of the same. Fig. 3 is a sectional view of the traveling-crane mechanism on the line $\alpha\alpha$ in Fig. 2.

In the drawings, A is the track, and A' the track-support, of a traveling crane, preferably supported by brackets B, secured to overhead beams B', as illustrated in Fig. 2, and preferably extending through a shop. Upon the track A there is mounted a traveling crane the general features of which—viz., the brackets C, forming the ends thereof, the trolley-wheels C', and the transverse shafts C²—are of the usual construction. The brackets C, however, extend down below the track-supports A' and have secured thereto a transverse horizontal I-shaped beam D, which forms a trolley-track D' for a trolley-hoist mechanism E.

In one of the brackets C there is mounted a latch c, operated by a depending cord c' and

adapted to engage a stop a on the track-support A', as illustrated in Figs. 2 and 3, so that the traveling crane can be firmly held at fixed points in its traverse. 60

Opposite each side of the traveling-crane supports A' there are mounted in suitable supports one or more jib-cranes F, the arms F' of which are preferably formed of I-shaped beams which form trolley-tracks F² for a traveling hoist mechanism E. The arms F' of the jib-cranes F are on the same horizontal plane as the I-beam D of the traveling crane, and when any one of the jib-crane arms F' are moved so as to be at right angles to the track-support A' and the traveling crane brought opposite thereto, as shown in Figs. 1 and 2, the jib-crane arms F' and I-beam D on the traveling crane will then coincide and form a continuous track F² D', as shown in Fig. 2, over which a trolley-hoist E will travel. To retain the arms F' at right angles to the track-support A', as above described, I provide a latch f, mounted on the crane-arm F' and provided with an operating-cord f'. This latch f is adapted to engage a stop a' on the track-support A' when the arm F' is at right angles therewith. 70 75 80

Referring to Fig. 1, I have shown two machines G and H, adapted to be reached and served by the jib-cranes F on that side of the shop and from which work can be hoisted and carried by one of the jib-cranes F and delivered to the traveling crane, so as to be deposited under the craneway or carried by the traveling crane to another part of the shop and delivered to another of the jib-cranes on either side of the shop, and vice versa, as may be desired. 85 90

In the drawings, it will be observed, I have shown the jib-cranes and the traveling crane as of the ordinary conventional construction, as my invention consists rather in the arrangement of the cranes with relation to each other and the modifications of construction necessary to adapt them to coöperate substantially as described than to the use of any particular type of either jib or traveling crane, as any form of such cranes could readily be arranged and modified in their construction so as to practically embody my invention. 95 100 105

Therefore having thus shown and described convenient mechanism embodying my invention, so as to enable others to utilize the same, what I claim as new, and desire to secure by Letters Patent of the United States, is—

1. The combination of a traveling crane, a

transverse horizontal trolley-track thereon, a jib-crane on one side of the line of travel of the traveling crane, a horizontal trolley-track thereon on the same horizontal plane with the trolley-track on the traveling crane, means for locking the jib-crane trolley-track at right angles to the line of travel of the traveling crane, means for locking the traveling crane so that the trolley-track thereon will coincide with the trolley-track on the jib-crane when it is at right angles to the line of travel of the traveling crane, and a trolley-hoist adapted to operate over both of said trolley-tracks when they coincide as aforesaid and pass from one to the other, substantially as set forth.

2. The combination of a traveling crane, tracks therefor supported from above, a transverse horizontal track on said crane below the track-support thereof, a series of jib-cranes on one or both sides of the traveling-crane supports, horizontal trolley-tracks on said jib-

cranes on the same horizontal plane with the trolley-track on the traveling crane, means for locking each of said jib-cranes at right angles to the track-support of the traveling crane, latch mechanism for locking the traveling crane in line with each of said jib-cranes when at right angles with the track-support so that the trolley-track on the traveling crane will coincide with the trolley-track on the jib-crane opposite thereto, and a trolley-hoist adapted to travel over the trolley-track on the traveling crane and the trolley-track on the jib-crane coinciding therewith, and from one to the other, substantially as set forth. 35

In testimony whereof I affix my signature in presence of two witnesses.

JOHN R. WHITTEMORE.
